UNITED STATES PATENT OFFICE.

HENRY S. HALE, OF PHILADELPHIA, PENNSYLVANIA, ASSIGNOR TO
HIMSELF, A. KILBURN, J. W. HALE, H. W. CURTIS, C. KILBURN,
AND WARREN HALE, OF SAME PLACE.

IMPROVEMENT IN MATS FOR PICTURE-FRAMES.

Specification forming part of Letters Patent No. **155,082**, dated September 15, 1874; application filed
March 5, 1874.

To all whom it may concern:

Be it known that I, HENRY S. HALE, of Philadelphia, Pennsylvania, have invented an Improved Mat for Picture-Frames, of which the following is a specification:

The object of my invention is to make a cheap imitation of solid wooden mats for picture-frames, by securing to a supporting-frame or stiffening-ribs thin veneer backed by a suitable fabric, which so re-enforces the wood as to enable me to engrave on the face ornamental grooves for receiving the gilding, in accordance with the mode of ornamentation now adopted.

In the accompanying drawing, Figure 1 represents a face view of the mat; and Fig. 2, a sectional plan, showing the fabric detached from the veneer; and Fig. 3, a sectional view, showing the stiffening-ribs at the rear of the mat.

I take ordinary veneer A, of the size of the desired mat, and secure to the back, with glue or other suitable cement, a strip, B, of canvas, muslin, canton-flannel, or other cheap suitable fabric, and then fasten to the back at all four edges the stiffening-strips D, which are sufficiently thin to permit the proper fitting of the mat into the rabbet of the picture-frame. After the fabric and strips have thus been secured to the back of the veneer, the front may be properly smoothed and polished, and scroll or other ornaments made, according to the taste of the manufacturer, by

engraving the wood and gilding the sunken parts made by the engraver's tool, after which the central opening, of an oval or other shape, may be made for the display of the picture, by cutting out the wood and its backing.

When very thin veneers of costly foreign woods are used, I glue to the back of the fabric a thin strip of ordinary pine or other cheap wood, so as to afford an additional re-enforcement of thin veneer, the narrow edging of stiffening-strips being secured to this backing of wood.

The mats thus manufactured are much cheaper, and quite equal in appearance to, and not so liable to split as, a solid mat, and are much more readily and economically manufactured than the mats made of several layers of veneers glued together.

I do not claim, broadly, a mat in which the veneer is re-enforced by a backing of fabric; but

I claim as a new article of manufacture—

In combination with a mat consisting of a veneer face having a backing of fabric, the supporting-ribs D, substantially as and for the purpose set forth.

In testimony whereof I have signed my name to this specification in the presence of two subscribing witnesses.

HENRY S. HALE.
